UNITED STATES PATENT OFFICE.

WILLIAM B. OLIVER, OF COLLINGSWOOD, NEW JERSEY, ASSIGNOR TO OLIVER ELECTRIC COMPANY, OF PHILADELPHIA, PENNSYLVANIA, A CORPORATION OF PENNSYLVANIA.

MICROTELEPHONE.

1,074,286.

Specification of Letters Patent. Patented Sept. 30, 1913.

Application filed July 27, 1909. Serial No. 509,858.

To all whom it may concern:

Be it known that I, WILLIAM B. OLIVER, of Collingswood, in the county of Camden and State of New Jersey, have invented 5 certain new and useful Improvements in Microtelephones, whereof the following is a specification, reference being had to the accompanying drawings.

The primary use for which my invention 10 is intended, is to assist the defective hearing of persons more or less afflicted with deafness, but obviously, the device is susceptible of other uses, which require a transmitting element having the following 15 characteristics,—great sensitiveness, susceptibility for extremely minute regulation, high power of magnifying sound, and capacity for so modifying the behavior of the diaphragm electrode as to damp or eliminate vibrations of a certain character. As 20 a result of these various features, it may be said that the device has the capacity for controllably selecting and amplifying certain sound vibrations, while minimizing 25 others.

Referring to the drawings, Figure I, represents a front view of the external casing of the instrument in a preferred embodiment thereof. Fig. II, is a vertical central 30 section through the casing and the instrument proper, on the line II, II, of Fig. I. Fig. III, is a front view, in elevation, of the diaphragm electrode, indicating certain damping devices mounted thereon. Fig. 35 IV, is a vertical transverse section through the casing and the instrument proper, on the line IV, IV, of Fig. II. Fig. V, is a view of the spring support for the main rear electrode. Fig. VI, is a sectional view on an 40 enlarged scale, through one of the pockets in the main rear electrode, showing the contents thereof and one of the adjustable secondary rear electrodes, which constitutes the bottom of said pocket. Fig. VII, is a view, 45 partly in section and partly in elevation, of a modified form of the internal casing, the external casing being similar to that shown in Fig. I. Fig. VIII, is a front view of the internal casing represented in Fig. VII. 50 I first describe the micro-telephone element which may be termed the transmitter, without reference to the particular form of casing, external or internal, which may be used in connection therewith.

55 The main support or housing 1, is of

metal, annular in form, and of approximately T-shaped cross section, as shown in Fig. II, the actual size being about that shown in said figure, or even smaller. A backing plate 2, preferably of aluminum, 60 or light metal, is supported upon the rear face of the housing 1, by means of screws 3, said screws being provided with insulating bushings 4, and the backing plate being also insulated from the housing by means of 65 an annular washer 5. The spring support 6, of the main rear electrode, rests against the inner face of the backing plate 2, said support being dish-shaped, and, as shown in Fig. V, provided with a plurality of radial slots 7, which permit relatively free spring action. The raised central portion, which is flat, is perforated by a plurality of holes, in this instance, six in number, arranged symmetrically as shown in Fig. V. 75

The main rear electrode 10, consists of a relatively-massive disk shaped block of carbon, having a central hole terminating in an enlarged cavity 13, for the reception of a nut 14, which is prevented from turning 80 therein, said nut engaging a screw 15, which passes through the central hole of the electrode 10, and of the spring support 6, and has a slotted head received within a countersunk opening in the center of the backing plate 2. By turning this screw in one direction, the main rear electrode 10, can be drawn upward toward the backing plate 2, against the tension of the spring support 6, and, by turning the screw in the opposite direction, the resiliency of the spring support 6, will cause the main rear electrode to move away from the backing plate. Thus the main rear electrode can be adjusted, 85 throughout a relatively large range of movement, toward or from the diaphragm or front electrode 22. By this arrangement I effect what may be termed the coarse adjustment of the electrodes. 90

The main rear electrode 10, is provided 100 with a plurality of countersunk conical recesses or pockets 11, in this instance five in number, symmetrically grouped around the central cavity 13, in registry with the holes 8, of the spring support. Said pockets are 105 filled with small carbon balls or granules 12. These balls or granules are of a diameter greater than the distance between the adjacent faces of the front and rear electrodes, so that the balls or granules are re- 110

tained in position by the rims of their respective pockets, and are not permitted to escape into the interspace between the proximate faces of the main, front and rear electrodes.

5 Referring to the enlarged view of Fig. VI, it will be seen that from the bottom of each pocket 11, a cylindrical hole 19, extends entirely through the main rear electrode. The opening of each hole is closed by means of a cylindrical carbon plug 20, mounted upon the end of a screw 18, whose threads run freely within the hole 19, and the registering outer hole 8, of the spring 10 support, but engage with a threaded registering hole in the backing plate 2. The end of the carbon plug 20, thus constitutes the bottom surface of the pocket, and by rotating the screw 18, the plug may be made 15 to move toward or from the front diaphragm 10. These carbon plugs constitute what may be termed the secondary rear electrodes, in that while they form a portion of the rear electrode as a whole, (being electrically in 20 communication with the block 10), they are independently adjustable toward or from the diaphragm, so that the carbon balls or granules may be held with any desired degree of pressure against the sides of their 25 retaining cavities and against the rear face of the front electrode. By this arrangement I obtain what may be termed the fine 30 adjustment of the electrodes, and also accomplish other desirable results, which will 35 be explained hereafter.

The front electrode 22 consists of a very thin diaphragm of carbon which rests against the front face of the housing 1, in electrical contact therewith, and is provided with 40 a washer 23, placed beneath the surface of a protecting diaphragm 24, these parts being clamped in position by means of the annular cap 25, which screws upon the exterior face of the housing 1, and overlaps the front 45 edge as shown in the sectional view of Fig. IV. The protecting diaphragm 24, is preferably constructed of mica or thin celluloid, and it may have perforations 28, as shown, or may be entirely imperforate if desired.

50 I prefer to mount upon the front face of the diaphragm, or front electrode 22, damping devices, whose general character I have indicated in Fig. III. One form thereof is a very thin leaden disk 45, cemented or 55 otherwise secured to the diaphragm 22. Other forms are exceedingly light metallic springs 46, 47, having disks of some material, such as fiber, which is not a conveyer of sound vibrations, interposed between 60 them and the electrode, said springs bearing very lightly against the protecting diaphragm 24. In commercially constructed telephones, damping springs have been 65 employed to modify the vibrations of the diaphragm, but in micro-telephones of the

present character, the extreme delicacy of the vibrations to be transmitted, prohibits the use of externally supported damping means, and hence I have found that in order to eliminate undesirable overtones it is necessary to mount the damping devices directly upon the diaphragm electrode itself, and to make them of such character as not only to be mechanically susceptible of this mounting, but as not to coarsen the damping effect.

70 The transmitter, is of course, to be included within an electric circuit, the connections being conveniently made as follows:—The insulated conducting wire 35, 80 enters through the hole 36, in the wall of the housing, and is connected with a clip 37, carried by the screw 38, so arranged with relation to the non-conducting bushing 4, and washer 5, respectively, as to be insulated from the backing plate, but electrically connected with the housing, which in turn is in electrical contact with the front electrode 22. The other conducting wire 39, enters through the hole 36, and is 85 attached to a clip 40, in circuit with the backing plate 2, and, through the spring support 6, with the main and secondary rear electrodes 10, and 18, respectively, but is insulated from the housing 1, by means 90 of the bushing 4, and washer 5. The device thus described constitutes a complete micro-telephone transmitter, and may be used without the external casing if desired, since 95 the diaphragm 24, protects the front electrode from injury. When, however, high sound-magnifying power is desired, I employ the external casing, shown in Figs. I, and II, which comprises the cylindrical cup-shaped shell 30, of such dimensions as 100 to leave a free space around and behind the instrument. The front portion of the shell is provided with an annular cap 31, fitting frictionally upon the rim thereof and extending radially inward to a distance 105 of about one-third of the radius of the external periphery of the casing. The casing is secured to the backing plate by means of 110 screws 33, or in any convenient manner.

115 In the arrangement shown in Figs. VII, and VIII, the external casing, corresponding to the parts 30, and 31 is of the same configuration, but the protecting diaphragm 42, is preferably made of relatively heavy metal, as compared with the light celluloid or mica diaphragm 24, and, instead of being a flat disk, is dished outwardly in approximate conformity with the cross-section of the cap 31. The protecting diaphragm 42, screws directly upon the housing 1, an annular washer 41, intervening between the front electrode 43, and the periphery of the diaphragm 42.

120 Ignoring for the present the external casing, it will be noted that the instrument 130

above described has certain characteristics which are of importance to its utility.

The capacity for what I have termed the coarse adjustment of the rear electrode, with 5 relation to the front electrode, facilitates the general assembling of the parts, and permits of a wide range of positions. On the other hand, that which I have termed the fine adjustment, which is afforded by 10 reason of the fact that the bottoms of the pockets in the rear electrode are adjustable toward and from the front electrode, enables me to attain the exact intimacy of contact between the front electrode and the carbon balls, or granules, which is most efficient 15 in any particular instrument, or best adapted to the requirements of any particular person whose defective hearing is to be remedied, the contents of each pocket being 20 also individually adjustable, and they may be therefore filled with different sizes of balls or granules and the proper degree of contact pressure insured.

When the instrument is employed as an 25 adjunct to defective hearing this susceptibility of minute regulation is of peculiar value, since mere loudness of sound is not the only factor in assisting the hearing, it being found that some persons can best hear 30 sounds of a peculiar character not directly dependent upon loudness. This characteristic of the instrument is also enhanced by the employment of damping devices directly mounted upon the front electrode, which 35 result in eliminating certain overtones. When however, the transmitter is employed with the external casing, and particularly that form shown in Figs. VII, and VIII, other highly valuable characteristics are 40 found to exist, these may be briefly described as follows:—

It is intended that the sound waves from any given source shall be received, in the first instance, upon the thin carbon dia- 45 phragm, which is presented in the direction of their approach, and hence I have applied the term "front electrode" thereto, as indicating the contemplated position of that element with relation to the source from 50 which the sound waves emanate.

The force of the waves is modified by the protecting diaphragm 24, or 42. As however, the housing 1, is not arranged in contact with the casing 30, a definite passage- 55 way exists, through which sound waves, after being deflected around the front edge of the internal casing, can pass to the rear and to act forwardly against the backing plate 2. This backing plate directly carries 60 the screws 18, upon which the secondary rear electrodes 20, are mounted and indirectly carries, through the embodiment of the spring support 6, the main rear electrode 10. The pressure due to the impinge- 65 ment of the sound waves, is therefore cumu-

lative:—that is to say, it acts directly upon the face of the front electrode 22, and acts in a contrary direction upon the rear face of the main rear electrode and secondary rear electrodes.

I believe it to be the case that the ordinary or normal method of operation of micro-telephones, is characterized by that fact that the front electrode (or that which is directly presented to the impingement of the sound waves), moves under the influence thereof, toward or from the rear electrode, and that the motion of the sound waves is also transmitted in the same direction to the rear electrode, so that to a 70 certain extent, the front and rear electrodes tend to move in unison, under the impingement of any given wave. Hence the microphonic effect is due to the differential movement of the two electrodes, in approximately the same direction at the same time.

In my invention, the arrangement, whereby direct access of sound waves to the rear face of the rear electrodes is attained, tends to produce a movement thereof in opposition 90 to the movement of the front electrode so that although to some extent, the normal movement of the two electrodes in unison may tend to occur, the movement of the rear one is opposed by the movement due to approach from the opposite direction. Hence, instead of a differential movement in the same direction, the extent whereof is determined by the relative mass and positions of the two electrodes alone, I am enabled to 95 obtain a cumulative effect, due to movements in opposite directions, or to a reduction of the attempt of the rear electrode to move in unison with the front one. The result is a 100 great intensification of the microphonic action, and a very marked increase in the volume of the sound.

I believe that the above explanation accounts for the fact that such practical increase in the volume and clearness of the 110 sound occurs, when my above described arrangement is used, but I do not however, desire it to be understood as making this theory a part of the essence of my invention. Furthermore, I have found that the microphonic action is improved by the interposition of the annular shield formed by the cap 31, which partly closes the front of the instrument. The most advantageous extent thereof being that above stated, *i. e.* the projection being about one-third of the total radius. This fact seems to be in harmony 120 with the explanation above given, in that the shield tends to prevent the direct impingement of sound waves upon the housing, and adjacent parts, and tends to limit such direct impingement to the central portion of the front electrode, so that their transmission to the rear electrodes through the housing itself 125 is modified, while at the same time, the pas- 130

sage to the rear of the instrument is maintained and the current of sound waves flows around it to exert their effect upon the back of the rear electrode.

5 I am of course aware that in certain microphone transmitters an enlarged casing has been provided so as to afford quite an extended area for the collection of sound, and that while the central portion of such 10 casing has been closed by a solid backing, openings have been formed at or near the periphery to convey the sound waves around toward the rear portion of the casing. In such instruments, however, the diaphragm, 15 which I have termed the front electrode, is placed at the rear of the instrument, so that the sound waves collected by the enlarged periphery are received by a diaphragm electrode facing in the opposite direction to that 20 from which the waves are supposed to emanate. This arrangement bears no resemblance to the organization which I have described, and lacks the capacity for producing the cumulative action above set forth. 25 This feature of my invention, I therefore believe to be characteristic and absolutely novel, and while its peculiar method of operation is enhanced by the other features which I have described relating to the adjustability of the electrodes I do not desire 30 to limit my claims to the presence of these other improvements.

In the foregoing description I have employed the term "front electrode" as a convenient one to describe the relatively thin carbon diaphragm electrode, which, in the 35 normal position of the preferred embodiment of the invention, is the one nearest to the source of sound, and have applied the correlative term "main rear electrode" as a 40 convenient one to describe the relatively massive carbon electrode which, under the conditions mentioned, is more remote from the source of sound; the term "secondary 45 rear electrode" having been employed to indicate the fact that the carbon granules may be appropriately considered as constituting a part of the rear electrode in contra-distinction to the front one. Since, however, the 50 terms "front" and "rear" when thus generally used, may be ambiguous for the purposes of distinguishing the invention from transmitters of the prior art, I have thought it best, in certain of the claims, hereinafter 55 made, to refer to the element heretofore called the "front electrode," as a "diaphragm electrode," and to the element heretofore termed the "main rear electrode," as a "carbon block electrode," the term "relatively massive," being employed to further 60 characterize the said block electrode in comparison with the relatively thin diaphragm electrode. I also employ the term "transmitter" as synonymous with the transmitting element of a micro-telephone. I also

employ the term "granules" as comprehensive of the small movable carbon elements, forming part of the variable electric circuit, whether they be in ball form or otherwise.

I claim:

1. In a transmitter, the combination of a diaphragm electrode; a relatively massive carbon block electrode provided with pockets; carbon granules arranged within said pockets; a spring mounting for the carbon block electrode, said spring normally tending to press said carbon block electrode toward said front electrode; and an adjusting screw, adapted to retract said rear electrode against the tension of the spring mounting, and to permit movement in the opposite direction under the resiliency of said mounting.

2. In a transmitter, the combination of a diaphragm electrode; a relatively massive carbon block electrode provided with pockets; carbon granules arranged within said pockets and in electrical connection with each other, whereby together with said carbon block electrode they form part of one electrical circuit; and means for varying the depth of said pockets, whereby adjustment of the pressure of the carbon granules may be effected without varying the position of the carbon block electrode with relation to the diaphragm electrode.

3. In a transmitter, the combination of a diaphragm electrode; a relatively massive carbon block electrode; carbon granules carried by said carbon block electrode; means for varying the adjustment of said carbon block electrode with relation to said diaphragm electrode; and independent means for varying the adjustment of the carbon granules with relation to said diaphragm electrode.

4. In a transmitter, the combination of a diaphragm electrode; a relatively massive carbon block electrode, provided with a pocket having an opening at the bottom thereof; carbon granules arranged within said pocket; a carbon plug arranged within said opening; and means for controllably shifting said plug.

5. In a transmitter, the combination of a diaphragm electrode; a relatively massive carbon block electrode having pockets open at the bottom; and plugs for closing the bottoms of said pockets; said plugs being mounted independently of said carbon block electrode, whereby said carbon block electrode and said plugs may respond differently to sound waves.

6. In a transmitter, the combination of a diaphragm electrode; means for completing a variable electric circuit therethrough; a spring carried by said diaphragm electrode; and a nonvibratory pad inserted between said spring and said electrode, substantially as set forth.

7. In a transmitter, the combination with a front diaphragm electrode and a rear relatively massive carbon block electrode; of means whereby the direct impingement of 5 sound waves upon the front surface of the diaphragm electrode is permitted, while the direct transmission of said waves to the front surface of the carbon block electrode is minimized; and means whereby other 10 sound waves are conveyed to impinge upon the rear surface of the carbon block electrode, substantially as set forth.

8. In a transmitter, the combination of a front diaphragm electrode; a relatively 15 massive rear carbon block electrode having pockets; carbon granules carried by said pockets; a mounting plate for said carbon block electrode arranged at the rear thereof; and a deflecting shell provided with a passage 20 way around said diaphragm electrode, and leading to said mounting plate, whereby the direct transmission of sound vibrations to the front of the carbon block is minimized and said carbon block electrode

is permitted to respond mainly to vibrations 25 impinging from the rear.

9. In a transmitter, the combination of a front diaphragm electrode; a relatively massive rear carbon block electrode containing 30 pockets; carbon granules in said pockets; a mounting plate for said carbon block electrode arranged at the rear thereof; and an inclosing shell having a reduced opening at the front and provided with a passage 35 way leading around said diaphragm to the rear of said mounting plate whereby the direct transmission of sound vibrations to the front of the carbon block electrode is minimized and said carbon block electrode is permitted to respond mainly to vibrations 40 impinging from the rear.

In testimony whereof, I have hereunto signed my name, at Philadelphia, Pennsylvania, this twenty-sixth day of July, 1909.

WILLIAM B. OLIVER.
